UNITED STATES PATENT OFFICE.

RENATO MINUTO, OF NEW YORK, N. Y., ASSIGNOR TO UNIVERSAL METAL SPINNING & STAMPING COMPANY, OF NEW YORK, N. Y., A CORPORATION OF NEW YORK.

DESIGN FOR A SHOWER-PAN FOR LIGHTING-FIXTURES.

49,362.

Specification for Design.

Patented July 11, 1916.

Application filed January 6, 1916. Serial No. 70,692. Term of patent 7 years.

To all whom it may concern:

Be it known that I, RENATO MINUTO, a subject of the King of Italy, residing at New York city, in the county and State of New York, have invented a new and Ornamental Design for a Shower-Pan for Lighting-Fixtures, of which the following is a specification, reference being had to the accompanying drawing, forming part thereof.

Figure 1 is a side elevational view of a

shower pan for lighting fixtures; and Fig. 2 is a plan view thereof.

I claim:—

The ornamental design for a shower pan for lighting fixtures, as shown.
